UNITED STATES PATENT OFFICE.

JOHN N. STEWART, OF CLEVELAND, OHIO.

HOLDER FOR TELEPHONE-RECEIVERS.

SPECIFICATION forming part of Letters Patent No. 299,288, dated May 27, 1884.

Application filed October 15, 1883. (No model.)

To all whom it may concern:

Be it known that I, JOHN N. STEWART, of Cleveland, in the county of Cuyahoga and State of Ohio, have invented new and useful 5 Improvements in Holders for Telephonic Receivers, of which the following is a specification.

These improvements relate to the receiving end of telephonic instruments, and consist 10 in the arrangement of two receivers to be applied to each ear of the operator, or a double receiver, whereby the sounds may be heard by both ears at the same time, the object being to provide a means of engaging both ears 15 for hearing the sounds, so that the hearer may not be annoyed by the confusion of sounds which are made by outside influences, enabling the hearer to hear the telephonic sounds more distinctly, and at the same time have both 20 hands free for other uses. Heretofore one hand has been required for holding the receiver to the ear, confining the hand to that use, and also leaving the other ear open and free to 25 hear other sounds, which confuse and render the telephonic sounds unintelligible. These objections my improvements entirely overcome. I accomplish these desirable results by arranging two ear-pieces on a frame or 30 tongs provided with a suitable spring for holding the receivers to the ears of the operator, said receivers being each connected by the wire, so that each simultaneously receive the telephonic sounds, the construction and arrangement being substantially as hereinafter 35 described and claimed.

In the accompanying drawing, the figure shows two levers hinged together near their lower ends and provided with an adjusting spring and screw for regulating the tension of 40 the spring, said levers having attached on their upper ends a telephonic sound-receiving ear-piece.

A B represent two arms of a pair of tongs,

bent into convenient form to adapt them for the use designed. Below the joint said levers 45 extend a short distance, and have interposed between the ends a spring, C, through which a rod, D, passes, having a head on one end, and the other provided with a screw-thread and a thumb-nut with which said spring may 50 be more or less compressed for regulating its tension. On the ends of the long levers are attached telephonic receivers E F, with their openings toward each other, and the said receivers are connected by the wire, so as to put 55 both in the electric circuit, whereby both receivers work in concert.

The manner of using my device is to take hold of the levers by each hand and spring them apart sufficiently, placing the receivers 60 against each ear, letting the bow hang beneath the chin. The tension of the spring compressing the levers will hold the device in place without further use of the hands for that purpose.

The manner of constructing the holder may be varied from that shown, and any other substantially the same be adopted. A spring-bow without joint may be employed, if desired; but the jointed levers are preferable, for 70 the reason that the tension of the spring can be adjusted to fit more conveniently various sized heads.

Having described my invention, I claim—
In double telephonic receivers, two levers, 75 A B, crossed and pivoted together and provided with spring C and adjusting-screw rod D, said levers supporting two receivers connected in the electrical circuit by wire, combined and operating as and for the purpose 80 specified.

JOHN N. STEWART.
